UNITED STATES PATENT OFFICE.

LORENZO D. GRANT, OF LANSINGBURG, NEW YORK.

DESIGN FOR A BRUSH.

SPECIFICATION forming part of Design No. 18,261, dated April 17, 1888.

Application filed February 1, 1888. Serial No. 272,691. Term of patent 7 years.

To all whom it may concern:

Be it known that I, LORENZO D. GRANT, a citizen of the United States, residing at the village of Lansingburg, in the county of Rensselaer and State of New York, have invented and produced a new and original Design for Brushes, of which the following is a description, reference being had to the accompanying drawings, forming a part thereof.

Figure 1 is a top plan view of my newly-designed brush. Fig. 2 is a side elevation of same.

A E represent a circular brush head; A', the handle. The upper surface of the head is provided with raised and depressed portions presenting the configuration of a star, C, the points D of which project over and beyond the periphery of the circular head. The handle, when seen in plan view, displays perforations 20 in the form of letters and in the form of a cir-

cle, a portion of the material forming the handle remaining within the circle in the form of a star, with the points intersecting the boundary-line of the circle.

I claim—

The design for a brush herein shown and described, the same consisting of a circular head having on its upper side raised and depressed surfaces, with radial projections, forming a raised outline in the shape of a star, the points 30 of the star terminating in the radial projections, and a lateral projection in the form of a handle, substantially as described.

In testimony whereof I have hereunto set my hand this 30th day of January, 1888.

LORENZO D. GRANT.
